UNITED STATES PATENT OFFICE.

ELMER ELLSWORTH WATSON, OF HAMILTON, OHIO.

INTERCHANGEABLE-KEY LOCK.

1,137,436.

Specification of Letters Patent. Patented Apr. 27, 1915.

Application filed September 24, 1909. Serial No. 519,364.

To all whom it may concern:

Be it known that I, ELMER E. WATSON, of Hamilton, in the county of Butler, and in the State of Ohio, have invented a certain 5 new and useful Improvement in Interchangeable-Key Locks, and do hereby declare that the following is a full, clear, and exact description thereof.

My invention relates to an improvement 10 in interchangeable key locks.

The object of my invention is to provide an interchangeable key lock of very simple construction, which at the same time is capable of adaptation to any one of a very 15 great number of different keys.

In general, the key lock which constitutes an embodiment of my invention is constructed in such a manner that any one of a given series of keys may be used to operate 20 the lock, but that when adjusted and locked by a certain key, only the key which has been used to lock the bolt can be used again to unlock the same. Again, when the lock has been locked, it is first necessary to in- 25 sert a guard key for the purpose of setting up a guard tumbler, before the lock can be unlocked by the locking and unlocking key. Furthermore, when the locking and unlock- 30 ing key has been withdrawn while the lock is in its unlocked position, it is first necessary to set up the lock by means of a guard key, before the lock can be again locked by means of the locking and unlocking key.

I have shown different embodiments of 35 my invention in the accompanying drawings, in which—

Figure 1 is a horizontal cross-section of a door equipped with one modification of the lock; Fig. 2 is an elevational view of said 40 lock with the cover plate removed; Fig. 3 is a similar view of another modification of my lock; Fig. 4 is a detail view of the key barrel; Fig. 5 is a rear elevational view of the interior of the modification shown in 45 Figs. 1 and 2, with a portion of the casing and bolt plate broken away; Fig. 6 is an elevational view of the rear guard tumbler shown in the modification appearing in Figs. 1 and 2; Fig. 7 is a similar view of the 50 rear guard tumbler used in the modification shown in Fig. 3; Fig. 8 is a similar view of the front guard tumbler used in both modifications; Fig. 9 is a detail view of the thumb-screw tightening mechanism used in

the second modification shown in Fig. 3, 55 and Fig. 10 is an elevational view of one of the auxiliary tumblers.

In the modification shown in Figs. 1, 2, 4, 5, 6 and 8 of the drawings, 1 is a door located within a wall 2. The door carries a 60 lock 3, which has a cylindrical boss 4 extending through the door to the outside thereof. The boss 4 carries a key cylinder 5 of the usual type. Said cylinder is provided with a talon 6, which operates upon the inner face of an inclosing shell 7 for the lock. The shell 7 is designed to be covered by means of a lid 8 in the usual manner. The talon 6 is designed to reciprocate a bolt 9, comprising a thin plate 10 carrying at its 65 outer edge a beveled head 11 projecting through the lock casing 7. The casing 7 carries near one end a pin 12 which guides a front guard tumbler 13, and a plurality of auxiliary tumblers 14. Each of the auxiliary tumblers 14 has a curved transverse slot 15 through which the pin 12 is designed to pass. The front guard tumbler 13 is situated upon the top of the auxiliary tumblers 14, and is provided with a longitudinal slot 70 15' to receive the pin 12. It also has at one end 16 a slot 17 and a projection 17'. The auxiliary tumblers 14 are provided at their corresponding ends with recesses 18 and projections 18' of the same general shape as 75 the end 16. The opposite end of each of the auxiliary tumblers is provided with a plurality of slots 19 and a projection 19'. In front of the slots 19, the flat plate 10 carries a rear racking stump 20, which is de- 80 signed to fit within one or more of the slots 19 in a manner to be hereinafter described. A rear guard tumbler 21 also co-operates with the rear racking stump 20, being pro- 85 vided with a recess 22 and a projection 23' 90 for this purpose. The rear guard tumbler 21 is slotted at 26 and pivoted upon a pin 24 projecting from the casing 7 upwardly. The slots 17 and 18 are designed to receive a 95 front racking stump 27 carried upon the flat plate 10. Each of the tumblers is pressed downwardly toward the key cylinder by a spring 28, each spring being adapted to slide upon the interior of the shell 7, and being attached at one end to one of the 100 tumblers in any approved manner.

The casing 7 is provided with a slot 29 to receive a pin 30 projecting therethrough,

which is pivoted upon an arm 31 normally spring-pressed into a vertical position by a spring 32. The plate 10 has a projection 33 upon its lower side intersecting the path of movement of the pin 30. This pin 30 is positioned in such a manner as to act as a stop for talon 6 in the retraction of the bolt so as to prevent the turning of the talon 6 sufficiently far to aline the key slots in the plug 10 5 and the base 4 to allow a retraction of the key.

The rear guard tumbler 21 is also provided with a recess 30', which is designed to register with the pin 30 when the latter is 15 moved out of the path of the talon 6, for the purpose of retaining the pin 30 in its depressed or inoperative position. Upon the insertion of a guard key for re-setting the lock, the pin 30 is automatically released 20 from the recess 30' by the lifting of the guard tumbler.

Assuming that the lock is in its unlocked position, the plate 10 has been withdrawn and the pin 30 to allow the withdrawal of 25 the locking and unlocking key with the bolt in unlocked position has been depressed by the finger so as to permit the rotation of the talon 6 beyond the position of the pin 30, a guard key is inserted into the lock to 30 move the rear guard tumbler 21 into engagement with the rear racking stump 20. Because of the presence of the slot 26 in the rear guard tumbler, upon the reverse rotation of the guard key for the purpose of 35 withdrawing the same, the pin 30 having been again manually depressed the rear guard tumbler 21 is moved into engagement with the rear racking stump 20, where it is held in this position by means of the 40 spring attached to said tumbler. The lock is now set up to any one of a number of keys for operating the auxiliary tumblers 14, which will bring any one set or group of the recesses 19 into engagement with the 45 rear racking stump 20. Upon the pin 30 now being released so as to permit its movement into a vertical position, by means of the spring 32, the bolt 9 carried upon the plate 10 can be moved into its locked position 50 by a further rotation of the key. As the bolt 9 reaches its locked position, the front ends of the auxiliary tumblers, and the corresponding end of the front guard tumbler 13, are released from engagement with 55 the front racking stump 27, the projections 17' and 18' engaging said front racking stump to limit the movement of the various tumblers. The key can now be withdrawn.

In order to unlock the lock, it is necessary 60 first to insert a guard key to move the front guard tumbler 13 into position opposite the front racking stump 27. Upon the reverse rotation of the guard key for withdrawing the same, the slot 17 is forced over the front 65 racking stump 27, so as to become engaged

therewith. The spring attached to the front guard tumbler maintains the same in the position in which it engages the front racking stump. The same key which has been used to lock the lock can now be inserted for 70 unlocking the same. Such key when rotated moves the recesses 18 of the auxiliary tumblers 14 into a position opposite the front racking stump 27. The plate 10 attached to the bolt 9 is then withdrawn by a further 75 rotation of the said key until the rear racking stump 20 has been withdrawn from engagement with the recesses 19 of the auxiliary tumblers 14 and the recess 22 of the rear guard tumbler 21. The rear ends of the auxiliary tumblers 14 now fall downwardly so as to move the recesses 19 out of 80 engagement with the rear racking stump 20. The recess 22 of the rear guard tumbler 21, however, is retained in a position opposite the rear racking stump, as this end of the rear guard tumbler rests upon the pin 30 when the latter is in its vertical position. So long as the pin 30 is in this position, the key used to unlock the lock can not be withdrawn, but is retained in the lock for the 85 purpose of re-locking the same. Should it be desired to remove this key, the same can be accomplished by depressing the pin 30 and moving the talon beyond the position of said pin. Under these circumstances, however, it is necessary, as described above, to re-set the rear guard tumbler before inserting the new unlocking and locking key 90 for the purpose of locking the lock. 95

Assuming that the unlocking and locking key has not been withdrawn, in order to lock the lock, it is merely necessary to rotate 100 said key in the reverse direction until the bolt 9 engages with the recess in the door opening.

In this modification of my lock, when the rear guard tumbler is operated by means of the corresponding guard key to move the recess 22 thereof into engagement with the rear racking stump 20, this movement is made possible by the presence of the slot 26 in said rear guard tumbler. Upon the locking movement of the lock thereafter, the rear guard tumbler 21 is moved forwardly 110 a slight distance by the engagement of the bottom of the slot 22 thereof with the rear racking stump 20. Upon a subsequent retraction now of the bolt 9, the recess 22 of the rear racking tumbler 21 will no longer 115 be retained in engagement with the rear racking stump 20, but will be only maintained in a position opposite said rear racking stump 20, by means of the pin 30 which supports the rear end of the rear racking tumbler.

The front guard tumbler 13 operates in a similar manner. The slot 17 thereof is moved into engagement with the front racking stump 27, through the agency of the 120 125

guard key, but when the bolt is retracted to unlock the lock, the front racking stump 27 coöperates with the bottom of the recess 17 in said front guard tumbler to move the latter a slight distance to the rear. When, therefore, the bolt 9 is again moved forwardly to lock the lock, the front guard tumbler 13 falls downwardly with the auxiliary tumblers 14, as all of these tumblers are now released from engagement 10 with the front racking stump 27.

In the modification shown in Figs. 3, 7 and 9, the parts are constructed and operate in the same manner as described in connection with the other modification, except as follows:—The thin plate 10 is provided with a rear auxiliary bolt member 34 having an arm 35 at its lower end, for the purpose of limiting the movement of the talon 6 in certain positions of said arm and an upper arm 36 at the upper end thereof, provided with a slot 37 to receive a projection 38 upon the main body of the plate 10. The auxiliary bolt member 34 also carries a rear racking stump 39. The pin 12 in this instance extends inwardly from the casing 7 between the main body of the bolt 10 and the auxiliary bolt member 34. A pin 40 is attached to the under side of the auxiliary bolt member 34 projecting into a slot 41 in the casing 7. A thumb screw 42 is provided on the end of the pin 40, so as to secure the auxiliary bolt member 34 in its adjusted position.

In the normal operation of this modification of my lock, the parts operate in substantially the same manner as described in connection with the modification above referred to, except that the rear guard tumbler 21 is normally held in engagement with the rear racking stump 39, and the talon 6 is prevented from rotating sufficiently far to permit the withdrawal of the locking and unlocking key by the presence of the lower arm 35 upon the auxiliary bolt member 34. Furthermore, in case it is desired to set the lock for a new key, the thumb screw 42 is loosened, and the auxiliary bolt member 34 moved longitudinally away from the plate 10 in its unlocked position. The rear racking stump 39 is thus released from the recesses in the rear guard tumbler 21 and the auxiliary tumblers 14. All of these tumblers are now pressed downwardly by the various springs attached thereto, and the talon 6 can be rotated a sufficient distance to permit the withdrawal of the key. It will be seen that a great many different permutations of the positions of the slots 17 in the front guard tumbler and the slot 22 in the rear guard tumbler, can be made, so as to cause the lock to be operated by a great variety of guard keys. Furthermore, it will be seen that a great many different permutations of the positions into which the auxil-

iary tumblers are to be thrown by the locking and unlocking key, can be made, thus providing for a great variety in the kinds of keys that can be used for this purpose. It will be seen, however, that although many 70 different keys can be used to operate a particular lock, in order to lock and unlock the same, each key of the series which is adapted to operate the lock for this purpose must be provided with proper projections so as 75 not to interfere with the front and rear guard tumblers. By varying the positions of the slots in the front and rear guard tumblers, it will consequently be seen that an entirely new series of keys can be provided 80 for locking and unlocking the lock. The projections upon the keys used for locking and unlocking the lock are, however, so arranged as not to bring the guard tumblers into registry with the racking stumps, so 85 as not to dispense with the necessity of guard keys.

While I have described my invention above in detail, I wish it to be understood that many changes may be made therein 90 without departing from the spirit of my invention.

I claim:—

1. In a device of the character described, the combination of a locking member, the member having a key slot, a key operated tumbler movable as a whole adjacent to the key slot and having a fulcrum adapted to be moved with the movement of the tumbler as a whole by the operation of a particular key for controlling the movement of the locking member, and a stump coöperating with the tumbler at one end thereof. 95
2. In a device of the character described, the combination of a locking member and a key-operated tumbler for controlling the movement of the locking member, said tumbler having a movable fulcrum adapted to be moved by the key, and an operative open-ended slot on each end. 105
3. In a device of the character described, the combination of a locking member, a member having a key-slot, a tumbler adjacent to the key-slot for controlling the movement of the locking member, a racking stump coöperating with the tumbler at each end thereof, and a movable pin for preventing, when in one position, insertion of a key and locking of the locking member, and when in another position, permitting said insertion and locking. 115
4. In a device of the character described, the combination of a locking member, a member having a key-slot, a tumbler adjacent to the key-slot for controlling the movement of the locking member, said tumbler having an operative slot on each end, and a movable pin for preventing, when in one position, the insertion of a key and locking of the locking member, and when in an- 125
- 130

other position, permitting said insertion and locking.

5. In a device of the character described, the combination of a locking member, a member having a key-slot, a plurality of tumblers adjacent to the key-slot for controlling the movement of the locking member, a stump coöperating with the tumblers at each end of each of the tumblers, and a movable pin for preventing, when in one position, the insertion of a key and locking of the locking member, and when in another position, permitting said insertion and locking.

15. 6. In a device of the character described, the combination of a locking member, a member having a key-slot, a plurality of tumblers adjacent to the key-slot for controlling the movement of the locking member, said tumblers having an operative slot on each end, and a movable pin for preventing, when in one position, the insertion of a key and locking of the locking member, and when in another position permitting said insertion and locking.

7. In a device of the character described, the combination of a locking member, a member having a key-slot, a tumbler adjacent to the key-slot for controlling the movement of the locking member, a stump coöperating with the tumbler at each end thereof, and a movable pin for preventing when in one position the removal of a key used to unlock the locking members, and when in another position permitting said removal.

40. 8. In a device of the character described, the combination of a locking member, a member having a key-slot, a tumbler adjacent to the key-slot for controlling the movement of the locking member, said tumbler having an operative slot on each end, and a movable pin for preventing, when in one position, the removal of a key used to unlock the locking members, and when in another position, permitting said removal.

50. 9. In a device of the character described, the combination of a locking member, a member having a key-slot, a plurality of tumblers adjacent to the key-slot for controlling the movement of the locking member, a stump coöperating with the tumblers at each end of each of the tumblers, and a movable pin for preventing, when in one position, the removal of a key used to unlock the locking member, and when in another position, permitting said removal.

60. 10. In a device of the character described, the combination of a locking member, a member having a key-slot, a plurality of tumblers adjacent to the key-slot for controlling the movement of the locking member, said tumblers having an operative slot on each end, and a movable pin for preventing, when in one position, the removal of a

key used to unlock the locking member, and when in another position, permitting said removal.

11. In a device of the character described, the combination of a locking member, a plurality of key-operated tumblers for controlling the movement of the locking member and a stump coöperating with the tumblers at each end of each of the tumblers, said tumblers having movable fulcrums controlled by the position of said locking member.

15. 12. In a device of the character described, the combination of a locking member, a plurality of key-operated tumblers for controlling the movement of the locking member, said tumblers having an operative slot at each end of each of said tumblers and having movable fulcrums controlled by the position of said locking member.

20. 13. In a device of the character described, the combination of a locking member, means requiring the insertion and operation of a guard key to unlock the lock, but dispensing with said guard key in the normal locking of said lock and means requiring the insertion and operation of the guard key in order to lock the lock when the locking key has been withdrawn.

25. 14. In a device of the character described, the combination of a locking member, means requiring the insertion and operation of a guard key to unlock the lock but dispensing with said guard key in the normal locking of said lock, and means for preventing the withdrawal of the locking key in the unlocked position of the lock, said last mentioned means being constructed to allow movement to permit the withdrawal of said key and the lock being so constructed as to require thereafter the insertion and operation of the guard key before locking the lock.

30. 15. In a device of the character described, the combination of a locking member, a member having a key-slot, a tumbler adjacent to the key-slot for controlling the movement of the locking member, a racking stump coöperating with the tumbler at each end thereof, and a movable abutment for preventing, when in one position, insertion of a key and locking of the locking member, and when in another position, permitting said insertion and locking.

35. 16. In a device of the character described, the combination of a locking member, a member having a key-slot, a tumbler adjacent to the key-slot for controlling the movement of the locking member, said tumbler having an operative slot on each end, and a movable abutment for preventing, when in one position, the insertion of a key and locking of the locking member, and when in another position permitting said insertion and locking.

17. In a device of the character described, the combination of a locking member, a member having a key-slot, a plurality of tumblers adjacent to the key-slot for controlling the movement of the locking member, a stump coöperating with the tumblers at each end of each of the tumblers, and a movable abutment for preventing, when in one position, the insertion of a key and locking of the locking member, and when in another position, permitting said insertion and locking.

18. In a device of the character described, the combination of a locking member, a member having a key-slot, a plurality of tumblers adjacent to the key-slot for controlling the movement of the locking member, said tumblers having an operative slot on each end, and a movable abutment for preventing, when in one position, the insertion of a key and locking of the locking member, and when in another position permitting said insertion and locking.

19. In a device of the character described, the combination of a locking member, a member having a key-slot, a tumbler adjacent to the key-slot for controlling the movement of the locking member, a stump coöperating with the tumbler at each end thereof, and a movable abutment for preventing when in one position the removal of a key used to unlock the locking members, and when in another position permitting said removal.

20. In a device of the character described, the combination of a locking member, a member having a key-slot, a tumbler adjacent to the key-slot for controlling the movement of the locking member, said tumbler having an operative slot on each end, and a

movable abutment for preventing, when in one position, the removal of a key used to unlock the locking members, and when in another position, permitting said removal.

21. In a device of the character described, the combination of a locking member, a member having a key-slot, a plurality of tumblers adjacent to the key-slot for controlling the movement of the locking member, a stump coöperating with the tumblers at each end of each of the tumblers, and a movable abutment for preventing when in one position, the removal of a key used to unlock the locking member, and when in another position, permitting said removal.

22. In a device of the character described, the combination of a locking member, a member having a key-slot, a plurality of tumblers adjacent to the key-slot for controlling the movement of the locking member, said tumblers having an operative slot on each end, and a movable abutment for preventing, when in one position, the removal of a key used to unlock the locking member, and when in another position, permitting said removal.

23. In a safety lock the combination of a sliding bolt provided with a detent, a plurality of adjacent tumblers engaged in common at one end by said detent in the retracted position of the bolt and a detent engaging said tumblers in relatively adjustable positions of elevations at the other end.

In testimony that I claim the foregoing I have hereunto set my hand.

ELMER ELLSWORTH WATSON.
